D. FINLEY

INSULATING CELL

Filed Dec. 29, 1919

UNITED STATES PATENT OFFICE.

DOZIER FINLEY, OF OAKLAND, CALIFORNIA, ASSIGNEE TO THE PARAFFINE COMPANIES, INC., OF SAN FRANCISCO, CALIFORNIA, A CORPORATION OF DELAWARE.

INSULATING CELL.

Application filed December 29, 1919. Serial No. 348,021.

To all whom it may concern:

Be it known that I, DOZIER FINLEY, a citizen of the United States, and a resident of Oakland, county of Alameda, and State of California, have invented a new and useful Insulating Cell, of which the following is a specification.

My invention relates to thermal insulating cells for construction purposes.

10 An object of the invention is to provide an efficient thermal insulation in the form of a construction unit.

Another object of the invention is to provide a construction unit of the character described which is impervious to water, and which possesses such inherent strength that it can be handled and transported without special protective measures.

The invention possesses other objects and 20 features of advantage, some of which, with the foregoing, will be set forth in the following description of the preferred form of my invention which is illustrated in the drawings accompanying and forming part 25 of the specification. It is to be understood that I do not limit myself to the showing made by the said drawings and description, as I may adopt variations of the preferred form within the scope of my invention as set 30 forth in the claims.

Referring to the drawings:

Figure 1 is a plan view of one of my insulating cells, a portion of the top wall and packing being broken out to disclose the structure. Figure 2 is a vertical sectional view through the cell. The plane of section is indicated by the line 2—2 of Figure 1. Figure 3 is a vertical sectional view through a wall insulated by my cells.

40 In building refrigerating rooms and similar structures cork blocks are customarily used for insulation. Because of inherent qualities such blocks will absorb as much as 40% of their weight in water. Furthermore 45 cork blocks possess but little inherent strength and are easily broken in handling. Broadly expressed, it is an object of the present invention to provide a substitute for cork blocks, and one which will be superior 50 to cork in insulating values, proof against absorption of moisture, and possessed of inherent strength ample to protect it from injury with ordinary handling. I accomplish this result by providing a preferably rectangular box or cell formed of a light material

such as fiber board, and packed with a light insulating material such as fibrillated redwood bark. The cell is closed and hermetically sealed and may then be used as a brick-like unit in constructing an insulating wall. 60

Referring to Figures 1 and 2, the cell comprises a box of any desired size, but which conveniently may be 2 inches thick, 12 inches wide and 36 inches long. It may be constructed after any desired pattern, but preferably is formed with side flaps 2 turned inwardly to a flush joint 3, and end flaps 4 overlying the side flaps and cemented thereto by sodium silicate or other suitable adhesive. In order to seal the joint 3 a strip 6 70 of heavy paper is adhesively united to the side flaps over the joint.

Compression members 7 formed of fiber board bent in the form shown are secured on the bottom of the cell by adhesive or 75 staples, and these form abutments for fixing the position of the side flaps and for preventing the crushing in of the sides. The abutments are left open at their ends so that the packing material may be inserted within 80 them. For packing the cell I have found that fibrillated redwood bark is suitable, and for each cubic foot of space I use about 72 ounces of the bark just as it comes from the shredding machines, that is to say, containing 85 both long hair-like fibers and dust-like particles. When the packing 8 is condensed to the degree indicated, it does not condense or shake down any further during the handling of the cells. 90

After the packing fiber is arranged in the box the upper side flaps are preferably secured by adhesive to the tops of the abutments, the upper end flaps secured to the side flaps and the upper sealing strip applied. 95 The cell is now ready for the waterproofing and this is done preferably by painting or mopping the surface with asphaltum. A heavy bituminous paint dissolved in a volatile solvent, or other suitable waterproof compound may be used. After application of the asphaltum, the surface is dusted over with wood flour to prevent the cells sticking together before use. Wood flour is preferred since it does not prevent 100 the coalescing of the asphaltum coating with the asphaltum used later in laying up the cells in a wall. 105

In Figure 3 I have shown how the cells are used in the vertical walls of a cold 110

storage room. The outer wall 12 against which the cells 13 are to be placed is coated with hot asphaltum and the cells are pushed firmly to a seat. One or more tiers of cells 5 are thus built up with a coating or thin layer 14 of asphaltum between the cells and the wall and over the inner surface of the last tier. This asphaltum used in laying up the cells combines readily with that 10 already covering the cell so that a perfect waterproof coating surrounds the cells, which are held securely together. To prevent mechanical injury to the cells an inside sheathing 15 is provided.

15 Instead of mopping the cell with asphaltum to waterproof it, I may enclose the cell in a sealed wrapper water-proofed by saturation in a bituminous compound.

In laying up the cells, it is desirable to 20 break joints. Fractional size cells will therefore be needed for this purpose as well as to fill in spaces of odd size. These may usually be supplied by cutting the cells to the desired size and sealing the cut ends 25 with heavy paper and asphaltum.

I claim:

1. An insulating unit comprising a cell, and a packing of fibrillated redwood bark arranged within said cell.
- 30 2. An insulating unit comprising a cell,

means for hermetically sealing said cell, and a packing of heat insulating material within said cell, said packing being of minimum density requisite to preclude further condensing thereof when in use.

35

3. An insulating unit comprising a fiber board cell, and a packing within said cell of substantially 72 ounces of fibrillated redwood bark to each cubic foot of enclosed space.

40

4. An insulating unit comprising a fiber board cell, fiber board abutments arranged between opposite walls of said cell, a packing of loose heat insulating material disposed in said cell to completely fill the same, 45 and a sheathing of waterproof material overlying the surface of said unit.

45

5. An insulating unit comprising a fiber board cell, a coating of bituminous compound on said cell, a packing of heat insulating material within said cell and a coating of wood flour over said bituminous coating.

50

In testimony whereof, I have hereunto set my hand at San Francisco, California, this 55 20th day of December, 1919.

DOZIER FINLEY.

In presence of—

C. S. EVANS.
